RADIO TUNER

Edward L. Barrett, La Grange, Ill., assignor to
Utah Radio Products Company, Chicago, Ill.,
a corporation of Illinois

Application May 21, 1938, Serial No. 209,253

6 Claims. (Cl. 74—10)

The invention relates to tuners for radio receivers and more particularly to tuners of the so-called station selector type which are adapted to position the tuning element of an associated radio receiver in such manner as to condition the same for the reception of signals from any selected one of a predetermined series of broadcasting stations. In such tuners a separate actuator is provided for each station tuning position and it is only necessary for the operator to select and move the actuator corresponding to the desired station as distinguished, for example, from the conventional dial type tuning device with which the tuning adjustment of the receiver is varied manually throughout a broad range until the frequency indicator dial shows the receiver to be tuned for the frequency of the signals from the selected station. Furthermore, the tuner herein contemplated is of a general type sometimes designated as "mechanical." In such a mechanical tuner, all of the power required for moving the receiver tuning element is derived from the movable actuators in contrast with the arrangement in so-called "electric" tuners in which the tuning element is driven directly by an electric motor controlled in its extent of movement so as to stop the tuning element in different station tuning positions by, for example, an apparatus such as that disclosed in my prior Patent No. 2,046,910, issued July 7, 1936. It will be understood, however, that the actuators of the mechanical type of tuner, as the term is used herein, are not limited to constructions in which the actuators are necessarily manually moved.

The general object of the present invention is to provide an improved form of mechanical tuner which is cheap to manufacture, rugged in construction, and which is smooth and easy, as well as precise in operation.

Another object of the invention is to provide a mechanical tuner embodying a novel form of station selecting cam and cooperating actuator of such character that a substantially constant force is utilized in moving the cam to tuning position thereby avoiding inadvertent shifting of the cam on its support as distinguished from the action in some forms of mechanical tuners heretofore proposed in which a decreasing force is required to move the cam with the result that an excessive force is actually applied at the end portion of its path of travel so that it is severely jarred when it comes to rest and tends to become very quickly misadjusted.

Still another object of the invention is to pro-

vide a mechanical tuner embodying a novel form of station selector actuator and associated cam by means of which the cam can be moved exactly to its station tuning position with a high degree of accuracy.

The invention also resides in various structural improvements in the arrangement for adjustably securing the cams in position on their associated supporting shaft.

Further objects and advantages of the invention will become apparent as the following description proceeds taken in connection with the accompanying drawings in which:

Figure 1 is a perspective view of a mechanical tuner embodying the present invention;

Fig. 2 is a transverse sectional view along the line 2—2 in Fig. 1;

Fig. 3 is a plan view of the tuner unit of Fig. 1;

Fig. 4 is an enlarged detail perspective view of a portion of the unit frame structure;

Fig. 5 is a diagrammatic view illustrating the range of positions of the cams with respect to the associated actuators;

Figs. 6 to 9 inclusive are diagrammatic views representing the various positions of the selector cams and associated actuators in the course of the tuning operation;

Figs. 10 and 11 are enlarged detail elevations of one of the cams and its associated actuator;

Fig. 12 is a detail perspective view of one of the selector cams illustrating particularly the means by which it is adjustably secured to its supporting shaft;

Fig. 13 is an enlarged detail longitudinal sectional view of one of the cams with the associated parts by which it is attached to the supporting shaft;

Fig. 14 is an enlarged detail perspective view of an anchor plate included in the cam supporting structure;

Fig. 15 is an enlarged detail view of one of the wire springs included in the cam supporting structure.

Referring more particularly to the drawings the invention has been shown herein as embodied in a mechanical station selector type tuner unit (Fig. 1) adapted to be incorporated in a radio receiver within any suitable type of cabinet or housing. Such units are ordinarily supplied to or made by radio set manufacturers and are built into the set during the course of its construction, although in some instances the tuner may be housed in a separate cabinet and connected to a complete receiver. The improved tuner here-

in illustrated is arranged to rotate a shaft 10 of a movable tuning element of a radio receiver such as an oscillatable variable condenser (not shown). In general the tuner rotates the shaft 10 to any selected one of a predetermined series of positions of angular adjustment in which the receiver is conditioned for the reception of radio signals from a corresponding series of broadcasting stations. A separate actuator is provided for obtaining each tuning position. These actuators are shown herein as being of the manually operable type and as including axially slideable actuator bars 11 carrying push buttons 12, although it will be understood that if desired, actuating means other than manual push buttons may be provided such, for example, as solenoids controllable at a distance. Upon depressing any selected one of a series of push buttons 12 the tuning element shaft 10 is rotated, through the medium of a novel form of cam selector mechanism hereinafter described, to the corresponding tuning position. Indicia may be provided on the faces of the push buttons 12 to show the particular stations for which each of them is adapted to tune the associated radio receiver.

Since the tuner unit illustrated is designed to be mounted within an enclosing cabinet with the push buttons 12 projecting through a suitable front covering panel (not shown) the supporting structure for the unit itself may be simply an unornamented open-type framework or chassis. In the illustrative embodiment this framework includes a pair of sheet metal end plates 13 joined by a sheet metal channel 14 of U-shaped cross-section (Figs. 2 and 4). The plates 13 are secured to the opposite ends of the channel 14 by suitable lugs 15. The particular lug construction shown forms no part of the present invention but is described more particularly and claimed in my copending application Serial No. 209,251, filed May 21, 1938. The actuator bars 11 are slidably supported for endwise movement in aligned apertures 16 and 17 formed respectively in the front and rear legs of the channel 14.

An oscillatable member or tuner shaft 19 is journaled in suitable bearings 18 (Fig. 1) attached to the chassis end plates 13. This tuner shaft is connected in driving relation with the radio receiver tuning element shaft 10. The conventional type of radio receiver variable condenser is oscillatable through a tuning range of approximately 180° but in order that the improved cam type selector mechanism herein disclosed may operate in the manner hereinafter described, it is necessary that the tuner shaft 19 oscillate through an arc of substantially less than 180°. Accordingly, a speed reduction connection is preferably provided between the shafts 10 and 19. This connection has been shown in the form of a pair of pulleys 20 and 21 fixed on the respective shafts and connected by an endless belt 22. The ratio of diameters of the pulleys may, for example, be three to four so that the shaft 19 will move through an arc of only 135° while the shaft 10 is moving through an arc of 180°. In some instances it is desirable to provide means in the tuner unit itself for positively limiting the arc of movement of the tuner shaft 19 rather than depending merely upon the limits of movement for the condenser attached to the shaft 10 and for this purpose stop pins 23 may be secured to the pulley 21 at suitably spaced points for the angle of movement desired and arranged to abut against a fixed stop pin 24.

A series of flat peripheral cams, designated

generally by the numeral 25 (Fig. 2), are carried by the tuner shaft 19. One cam is provided for each station selector push button 12. Each of these cams 25 is eccentrically mounted on the shaft 19 and is adjustable about its axis so that the major axis 26 of each of the generally rectangular cams 25 (Fig. 5) can be displaced, from one extremity of a predetermined range of adjustment, an arcuate distance bearing a predetermined ratio to the displacement of the radio receiver tuning element, necessary to accomplish tuning of the receiver for the reception of signals from the station which the particular cam represents. The predetermined ratio is the same as the ratio of speeds of the shafts 10 and 19. For example, if the radio receiver condenser must be displaced 60° from one extremity of a range of movement of 180° in order to tune the receiver for signals from a station "A," then the corresponding selector cam 25 is adjusted to a position in which it is displaced three-fourths of 60° or, in other words, 45° from the corresponding extremity of its range of adjustment. This calculation is made on the basis of a three to four ratio of speeds for the shafts 10 and 19 as described. In the event that a special condenser is used having a range of adjustment of only say 135°, then of course the ratio noted may be made one to one and the tuner shaft connected directly to the condenser shaft.

Upon reference to Fig. 2 it will be seen that the cams 25 are arranged in a generally fan-like configuration about the axis of the shaft 19. If the range of movement of the shaft 19 is 135°, then the range of adjustment of the cams 25 is also 135°. Accordingly, the extreme positions which the major axis 26 of the cams 25 can occupy, either by virtue of adjustment or oscillation of the shaft 19, lies within an arc of 270° (see Fig. 5). This has been found to be a desirable range of movement for practical operation. It is small enough to insure positive actuation of the cams by the actuators, and yet great enough to allow a large range for accurate positioning of the cams. As to the latter point, it is desirable to have the range of adjustment as nearly as great as the range of movement of the condenser as is possible since any error in positioning the cams will be multiplied in positioning the condenser by the radio between their ranges of movement. No implication is intended by the term fan-like, as applied to the cam arrangement, that the cams must be disposed at progressively different angles as shown in Fig. 2. They will, of course, be disposed at different angles corresponding to the tuning adjustments for the stations which they represent, but within the ranges of positions described.

In order that the actuators 11 shall be operative to shift the cams 25 in either clockwise or counterclockwise direction to a predetermined mid-position, the actuators are preferably disposed for movement along a line which bisects the angular area lying outside the 270° range of positions for the cams (Fig. 5). The actuators 11 are preferably fashioned as stampings from sheet metal and each of them is provided with a fork-shaped inner end including laterally spaced longitudinal upper and lower projections 27 and 28 located on opposite sides of the axis of rotation of the cams 25. These forked actuators are dimensioned to embrace the butt ends of the cams 25 and are located generally opposite such end portions rather than opposite the elongated outer end portions. The actuators are

yieldably retained in their retracted positions (Fig. 2) by helical tension springs 11^a disposed in suitable recesses in the actuators and anchored at their opposite ends to the respective actuators and to the front leg of channel 14. The guide apertures 17 in the channel are enlarged at their centers to permit free passage of the springs (Fig. 4).

In the operation of the tuner the one of the actuators 11, corresponding to the station selected, is pushed inwardly. If the one of the cams 25 associated with the selected actuator is, for example, located above its mid-line position (Fig. 6) the upper actuator projection 27 strikes the cam and causes it to rotate in a counter-clockwise direction until it reaches its predetermined tuning position shown in Fig. 8. Similarly, if the selected one of the cams 25 is, at the time of movement of its associated actuator, located below the center-line of the path of the actuator, the second or lower projection 28 on the actuator (Fig. 7) strikes the cam so that it is oscillated in a clockwise direction to the predetermined position of Fig. 8. In this way the cams 25 may be selectively moved to a predetermined position to tune in the corresponding station irrespective of the direction or extent of their displacement from this position at the time they are contacted by the actuator. It will also be noted that the length of stroke of the actuator is always constant. As soon as the actuator has been pushed fully in to complete rotation of the cam it may be released to return to its initial position (Fig. 9) under the bias of the spring 11^a. In their retracted positions the shoulders on the outer sides of the forked ends of the actuators 11 abut against the inner face of the outer wall of the U-shaped frame channel 14 (Fig. 2). The cams remain in adjusted position until another actuator is moved since no biasing force or the like is applied to the shaft 19 and accordingly the actuators need not be locked or retained in engagement with the cams.

For the actuators 11 to be able to rotate the cams 25 as described above it is necessary, as will be seen from an inspection of Figs. 6 and 7, that the cams should be displaced at least some little distance above or below the path of the actuator at the point of initial contact therebetween. Otherwise if the elongated end of the cam is facing directly toward the actuator in a dead center position the actuator will be ineffective to move the cam. For that reason the range of possible positions for the cams must be limited to substantially less than 360° in the manner described above, and preferably the range should be substantially 270° for best practical operation.

Precision of location of the cams 25 in their final tuning position is insured by the camming action of complementary abutting surfaces formed on the actuators 11 and the cams 25. In the preferred construction illustrated, flat surfaces 29 are machined on the butt end portions of the cams and are disposed to fit snugly against complementary flat surfaces 29^a on the bottom walls of the recesses formed in the forward ends of the fork-shaped actuators 11. The fork-shaped actuators are dimensioned to embrace the butt ends of the cams and as the cams move into their final tuning positions, the flat surfaces 29^a on the actuators come into contact with the lower outer corners of the cams and push the cams into their final position. The comple-

mental flat surfaces 29 and 29^a can be machined to fit with nicety and at small expense so that very precise location of the selector cams in their final tuning positions is achieved.

In order to insure smooth and easy operation of the tuner upon the application of a uniform force to the actuators 11 throughout their working strokes a special shape for the selector cams 25 is preferably utilized. For this purpose recesses are formed in the side edges of the cams so as to provide curved shoulders 30 thereon facing generally toward the butt ends of the cams. These shoulders 30 are so dimensioned or located on the sides of the cams that they will be contacted by one or the other of the actuator projections 27 or 28 as the cams move through the last 90° of their oscillatory movement and before reaching their final tuning position. The contour of the cam edges described prevents any jamming of the actuators against the cams during the final 90° of cam movement since the projections 27 or 28, abutting against the shoulders 30, apply a rotative force thereto in a line of action highly effective to cause rotation. The ends of the projections 27 and 28 are slightly rounded on their active edges to further insure smooth sliding motion. As a result, a substantially constant force is required to move the cams throughout the working strokes of the actuators.

The constant force type of operation described above is to be distinguished from that resulting from the use of other types of cams such, for example, as heart-shaped cams rotated by a roller type actuator which engages the cam periphery and finally enters the recess in the crown of the cam. With such heart-shaped cams a much greater force is required to initiate the rotation of the cam than to complete it. In a manually operated push button type tuner, the operator cannot very well decrease the amount of force exerted on the push button as it moves inwardly and consequently, if he has to exert a large force to start the selector mechanism movement, that same large force will be continued throughout the actuator stroke. The application of an excessive force at the completion of the stroke tends, however, to jar and dislodge the cams and spoil their adjustment on their supporting shaft so that they quickly become misaligned. In the improved construction herein disclosed, such inadvertent jarring of the selector cam parts is entirely obviated.

An adjustable connection is preferably provided between the selector cams 25 and their supporting member or shaft 19 so that the cams can readily be shifted to definite angular positions about the shaft for initially adjusting or readjusting the tuner for a predetermined list of stations. For this purpose the cams 25 are frictionally mounted on the shaft 19, the cams being provided with notches 31 in their butt ends which embrace the shaft. The sides of these notches are tapered as, for example, with a taper of about 2° so that the cams will wedgingly engage the shaft. A pair of generally U or hairpin-shaped resilient wire springs 32 yieldably urge each of the cams into such wedging engagement with the shaft. These wire springs are disposed on opposite sides of each cam and the base portions thereof are seated in peripheral annular grooves 33 formed in the shaft on each side of the respective cams (Fig. 13). The legs of the U-shaped wire springs 32 are bowed out somewhat and their bent ends are hooked over

ears 35 formed at the four corners of small rectangular sheet metal anchor plates 34 (Figs. 12 and 14) positioned on the outer ends of each of the cams 25. Each of these plates is held in position on the end of the associated cam by a centrally located slot 36 struck out from the plate and fitting in a complementary recess in the cam end surface. In adjusting the cams 25 initially for some selected list of stations, it is not necessary, with the apparatus disclosed, for the operator to have access to the interior of the unit. All of the adjustment manipulations can be carried out very simply and easily, even by an unskilled operator, from the exterior of the device. There are but two steps in the operation. First, the operator depresses a selected push button thereby rotating the associated cam until it is in its tuning position (Fig. 8). Instead of releasing the push button, however, as in the normal tuning operation, the operator retains the push button depressed and furthermore forces it inwardly with more than the usual pressure required. As a result, the legs of the resilient wire springs 32 are straightened out and the cam is dislodged from the shaft and moved a short distance radially away from it although still retained against rotation by the actuator fork which embraces the butt of the cam. The extent of radial displacement of the cam is limited by the contact of the shaft 19 against the bottom of a complementary notch 29^b formed in the forward face of the actuator so that the springs 32 will not be stressed beyond their elastic limit and thus be permanently deformed. With the selected cam thus released from the shaft 19 and held against rotation with respect to it, the second step in the adjustment operation is carried out. This second step consists simply of rotating the shaft 19 manually until the selected broadcasting station has been tuned in on the associated radio receiver. When the tuner shaft has been rotated to such point the selected actuator is released and the displaced cam snaps back into wedging engagement with the shaft due to the resiliency of the springs 32 so that the cam is precisely positioned for thereafter tuning in the newly selected station. The same series of operations is repeated for positioning each of the various selector cams for a corresponding series of station tuning positions. After having once been initially adjusted in this manner, it is only necessary for the operator to depress the push button corresponding to a selected station in order to tune the radio receiver for the reception of signals from that station, in the manner heretofore described. Although a particular embodiment of the invention has been shown and described in some detail for purposes of explanation of its various novel features, there is no intention to limit the invention thereby to such embodiment but, on the other hand, the appended claims are intended to cover all modifications and alternative constructions within the spirit and scope of the invention.

I claim as my invention:

1. A mechanical station selector type tuner for a radio receiver comprising, in combination, an actuator movable generally rectilinearly and having a recess in its forward end bordered by spaced forwardly projecting portions on opposite sides thereof, an elongated generally flat peripheral cam positioned in front of said actuator and lying in the plane of said projecting por-

tions of said actuator, means for supporting said cam for oscillation in said plane about an axis longitudinally eccentric to the center of said elongated cam and transverse to the path of movement of said actuator and with the outermost end of said cam facing generally away from said actuator and never directly toward the same, means for connecting said cam in driving relation with a tuning element of a radio receiver, and means for moving said actuator toward said cam to cause said projecting portions of said actuator to contact alternative adjacent edges of said cam and push the same around to a predetermined position in which the longitudinal axis of said elongated cam projects away from said actuator in substantial alignment therewith, said cam being provided with inset shoulders on opposite side edges thereof facing generally toward the butt end of said cam and dimensioned to be contacted by said projecting actuator portions to prevent jamming of the actuator against the cam as the latter is pushed through the last 90° of its rotation toward said predetermined position from either side thereof.

2. A mechanical station selector tuner for a radio receiver comprising, in combination, a flat axially movable actuator bar having a forked forward end including two forwardly projecting spaced arms defining a recess therebetween, an elongated generally flat peripheral cam lying in the plane of said actuator bar and in front of the forward end thereof, means supporting said cam for oscillation in said plane about an axis longitudinally eccentric to the center of said elongated cam and transverse to the path of movement to said actuator and with the outermost end of said cam facing generally away from said actuator and never directly toward the same, means for connecting said cam in driving relation with a tuning element of a radio receiver, and means for moving said actuator toward said cam to cause said projecting arms of said actuator to contact alternative adjacent edges of said cam and push the same around to a predetermined position in which the longitudinal axis of said elongated cam projects away from said actuator in substantial alignment therewith, said cam being provided with curved inset shoulders on opposite sides thereof facing generally toward the butt of the cam and dimensioned to be contacted by said projecting actuator arms to prevent jamming of the actuator against the cam as the latter is pushed through the last 90° of its rotation toward said predetermined position from either side thereof, said recess in said actuator being dimensioned to embrace the butt end of said cam when the latter is in said predetermined position, the bottom of said recess and said butt end of said cam being provided with complementary surfaces for locating said cam precisely in said predetermined position.

3. A station selector tuner mechanism comprising, in combination, a rotatable shaft adapted to be connected to a radio receiver tuning element, a plurality of station selector cams disposed side by side along said shaft and projecting radially therefrom at various angles corresponding to different station tuning positions of the receiver tuning element, means including a complementary series of actuators selectively engageable with said cams for rotating the same to predetermined tuning positions, and means for utilizing said actuators to adjust the angular positions of said cams on said shaft, said last

named means including means for yieldably holding said cams in position on said shaft by applying a biasing force thereto radially of the shaft and in a direction to be in alinement with the lines of action of said actuators when said cams are in said predetermined position, whereby said actuators may be utilized to oppose and overcome said biasing force to release said holding means and permit manual rotation of said shaft with respect to selected ones of said cams.

4. A station selector type tuner mechanism comprising, in combination, a rotatable shaft adapted to be connected to a radio receiver tuning element, a plurality of elongated peripheral station selector cams projecting radially from said shaft within an arc of substantially less than 180°, each of said cams being provided with a tapered notch in the butt end thereof embracing said shaft, means for yieldably urging each of said cams toward said shaft into wedging engagement therewith for holding said cams in selected positions of angular adjustment about the shaft axis corresponding to various station tuning positions of the receiver element, and means including a complemental series of actuators engageable selectively with said cams for not only rotating the cams to a predetermined tuning position but for also engaging the butt ends thereof and forcing said cams away from said shaft to release said wedging engagement and permit manual rotation of said shaft while holding said cams against rotation to thereby adjust the angular positions of said cams on said shaft, said actuators having recessed forward ends dimensioned to receive the butt ends of said cams when the latter are in tuning position.

5. A station selector type tuner mechanism comprising, in combination, a rotatable shaft adapted to be connected to a radio receiver tuning element, a plurality of elongated peripheral station selector cams projecting radially from said shaft within an arc of substantially less than 180°, each of said cams being provided with

a tapered notch in the butt end thereof embracing said shaft, means including a spring for yieldably urging each of said cams toward said shaft into wedging engagement therewith for holding said cams in selected positions of angular adjustment about the shaft axis corresponding to various station tuning positions of the receiver element, and means including a complemental series of actuators engageable selectively with said cams for not only rotating the cams to a predetermined tuning position but for also engaging the butt ends thereof and forcing said cams away from said shaft to release said wedging engagement and permit manual rotation of said shaft while holding said cams against rotation to thereby adjust the angular positions of said cams on said shaft, said actuators having recessed forward ends dimensioned to receive the butt ends of said cams when the latter are in tuning position, the base portions of said actuator recesses being dimensioned to engage said shaft at the end of a predetermined movement of said actuators toward the same to thereby limit the extent of displacement of said cams from said shaft and the strain placed upon said springs.

6. A station selector tuner mechanism comprising, in combination, a rotatable shaft adapted to be connected to a tuning element of a radio receiver, a generally flat peripheral station selector cam disposed transversely with respect to said shaft, said cam having a tapered notch in one edge thereof embracing said shaft, said shaft having annular grooves in the surface thereof on each side of the shaft, and means including resilient U-shaped wire springs fitted in said grooves and extending along the opposite sides of said cam with the outer ends of the arms thereof releasably secured to said cam for yieldably urging said cam into wedging engagement with said shaft, whereby said cam may be disposed in any selected position of angular adjustment about the shaft axis.

EDWARD L. BARRETT.
